Attorney

UNITED STATES PATENT OFFICE.

ARTHUR W. SHARRARD, OF CHELAN FALLS, WASHINGTON.

FRUIT-PICKING BAG.

1,354,220.

Specification of Letters Patent. Patented Sept. 28, 1920.

Application filed May 25, 1920. Serial No. 384,197.

To all whom it may concern:

Be it known that I, ARTHUR W. SHARRARD, a citizen of the United States, residing at Chelan Falls, in the county of Chelan and 5 State of Washington, have invented certain new and useful Improvements in Fruit-Picking Bags, of which the following is a specification.

My invention relates to improvements in 10 fruit picking bags.

An important object of the invention is to provide a bag of the above mentioned character, having means to evenly distribute the weight or pull upon the shoulders near the 15 neck and the lower portion of the back, at the same time maintaining the bag proper in a substantially upright position so that its lower end is suitably spaced from the knees of the picker, whereby he may conveniently 20 walk, or climb up and down a ladder, without liability of injuring or bruising the fruit by striking the same with the knees.

A further object of the invention is to provide a supporting frame, having a large 25 area to contact with the abdomen, and so constructed that it is simple, strong, and inexpensive to manufacture.

A further object of the invention is to provide eyes upon the main frame, serving 30 for connection with the supporting and retaining straps, and also to engage with reinforcing strips serving to cover the eyes and as attaching means for the bag.

Other objects and advantages of the invention will be apparent during the course 35 of the following description.

In the accompanying drawings forming a part of this specification and in which like numerals are employed to designate like 40 parts throughout the same,

Figure 1 is a perspective view of a fruit picking bag embodying my invention,

Fig. 2 is a central longitudinal section through the same,

Fig. 3 is an enlarged perspective view of the bag, seen from the rear side, the lower portion being broken away,

Fig. 4 is a perspective view of the frame,

Fig. 5 is a side elevation of one of the 50 covering and securing straps, parts being broken away.

In the drawings, wherein for the purpose of illustration is shown a preferred embodiment of my invention, the numeral 10 designates a supporting frame, as a whole, which 55 is preferably formed of a section of stiff wire, bent for providing an upper horizontal portion 11, which is longitudinally curved, and bent at one end to form a vertical eye 12. The wire extends from the 60 eye 12 in a vertical transverse end 13, bent into a vertical eye 14. From the eye 14 the wire is extended in the lower horizontal portion 15, which is longitudinally curved, and disposed parallel with the upper portion 11. 65 At its end, portion 15 is bent into a vertical eye 16, and the wire is continued in a vertical end 17, provided at its upper end with a vertical eye 18. From the eye 18 the wire is extended in a horizontal suspension portion 70 19, which is longitudinally curved, and has vertical eyes 20 and a horizontal eye 21 formed therein, as shown. The free end of the horizontal portion 11 is bent into a hook 22, which engages within the eye 18, and receives 75 therein the portions of the wire, which cross, as shown. The free end of the suspension portion 19 is bent into a hook 23, which engages in the eye 12, in a similar manner.

The numeral 24 designates diagonal elements or braces, preferably formed of stiff wire, having their lower ends bent into eyes or hooks 25 engaging within the eyes 14 and 16, and receiving therein the portions of 85 wire which cross, as shown. The upper ends of the braces 24 are bent into hooks 26, engaging within the eyes 20, and receiving therein the portions of the eyes which cross, 90 as shown.

The numeral 27 designates a bag portion, formed of suitable flexible material, such as stout cloth. This bag portion is tubular and has its upper and lower ends open. The upper end of the bag portion is extended 95 within the horizontal frame, embodying elements 11 and 19, and is folded outwardly and downwardly over this frame in the form of a hem 28, stitched at 29. Suitable openings are cut in the hem for the passage of the 100 vertical and horizontal eyes, as is obvious. The numeral 30 designates reinforcing and

covering strips, extending forwardly about the vertical eyes 20, and having their inner ends converging and stitched to the hem 28, at 31. Similar strips 32 are provided for the eyes 12 and 18, which are also secured to the inner side of the bag portion.

The numeral 33 designates shoulder straps, which are preferably longitudinally adjustable, and these shoulder straps are provided 10 at their forward ends with loops 34, preferably formed of leather, passing through the vertical eyes 20. These loops, together with the strips 30, substantially cover the vertical eyes 20, thereby preventing the fruit from 15 being bruised by contact therewith. At their opposite ends, the shoulder straps 33 have detachable hooks 35, to engage with the lower eyes 16.

I provide a waist-strap 36, which is preferably longitudinally adjustable, and one 20 end of this strap is permanently secured to the upper eye 12, while its opposite end carries a detachable hook 37, to engage within the eye 18. Particular attention is called to 25 the fact that the portions 11 and 15 and ends 13 constitute a rectangular upright frame, adapted to contact with the abdomen, and that the shoulder straps 33 connect with the bottom of this abdomen contacting frame, 30 while the waist-strap 36 connects with its top. This is an important feature of the invention, as it equally distributes the weight or pull upon the shoulders and the lower portion of the bag, and also maintains the 35 bag portion substantially perpendicular.

The lower end of the bag portion is formed open, and is closed to prevent the spilling of the contents, by folding the same transversely and also diagonally, as shown. 40 A strap 37 is attached to the lower end of the bag portion, and carries a snap-hook 38, preferably faced inwardly for convenience of operation. This snap-hook is adapted to detachably engage in a loop 39, secured to a strap 40, the upper end of which is passed through the inclined eye 21, as shown in Fig. 4, and the portions of the strap are secured together by a rivet or brad 42, as shown. When the hook 38 engages in the 45 loop 39, the bag portion has the maximum holding capacity, and when this hook engages within the inclined eye 21, the holding capacity is reduced to the minimum.

In the use of the bag, the straps 33 are 55 placed about the shoulder of the picker, with the arms extending between them, while the strap 36 extends about the waist. It is obvious that the supporting frame is not only pivoted upon the lower eyes 14 and 16, but 60 also is held horizontally by the waist-strap 36. This means enables the weight of the bag and its contents, to be placed upon the shoulder straps and waist-straps, which thus have a compensating action and evenly distribute the pull upon the shoulders and 65

lower portion of the bag. This is very important, as in the ordinary bag, the entire load is suspended from the shoulders, particularly at the back of the neck, which becomes fatiguing after hours of work. 70

When the bag portion is filled with fruit, its contents may be emptied by opening its lower end.

It is to be understood that the form of my invention herewith shown and described is to be taken as a preferred example of the same, and that various changes in the shape, size, and arrangement of parts may be resorted to without departing from the spirit of my invention, or the scope of 75 the subjoined claims.

Having thus described my invention, I claim:

1. A fruit picking bag of the character described, comprising a supporting frame 85 embodying an abdomen engaging portion having upper and lower members, and a suspension element carried by the upper member; a bag portion secured to the upper member and the suspension element, shoulder straps connected with the suspension element at points spaced from the upper member and having their opposite ends connected with the lower member, and a waist-strap connected with the ends of the upper 90 member.

2. A fruit picking bag of the character described, comprising an abdomen engaging frame, of a substantial height, a suspension element connected with the top of the frame, 100 a bag portion secured to the top of the frame and the suspension element, shoulder straps secured to the suspension element at points spaced from the top of the frame and having their upper ends connected with the frame at its bottom, and a waist-strap connected with the ends of the frame at its top.

3. A fruit picking bag of the character described, comprising a supporting frame 105 formed of a section of wire bent into a longitudinally curved abdomen engaging frame including upper and lower members, and a suspension element carried by the upper member, diagonal braces connecting the lower member and the suspension element, a 110 bag portion carried by the upper member and the suspension element, shoulder straps having forward ends secured to the suspension element at points spaced from the upper member and rear ends connected with the 115 lower member, and a waist-strap secured to the lower member.

4. A fruit picking bag of the character described, comprising a supporting frame 120 embodying a longitudinally curved abdomen engaging frame provided at its corners with eyes, a forwardly projecting suspension element secured to the upper corners of the longitudinally curved frame and having eyes formed therein, diagonal braces engag- 130

ing within the lower eyes and in the eyes of the suspension element, shoulder straps connected with the eyes of the suspension element and the eyes at the lower corners 5 of the longitudinally curved frame, a waist-strap connected with the eyes at the upper corner of the longitudinally curved frame, and a bag portion secured to the suspension element.

In testimony whereof I affix my signature **10** in presence of two witnesses.

ARTHUR W. SHARRARD.
